UNITED STATES PATENT OFFICE.

EDWARD N. GUCKERT, OF TOLEDO, OHIO.

BANJO.

1,412,239.

Specification of Letters Patent. Patented Apr. 11, 1922.

Application filed July 18, 1921. Serial No. 485,483.

To all whom it may concern:

Be it known that I, EDWARD N. GUCKERT, a citizen of the United States, and a resident of Toledo, in the county of Lucas and State of Ohio, have invented a certain new and useful Banjo; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to musical instruments and particularly to banjos.

It has been customary in some cases to provide banjos with double rims spaced apart to form a sound chamber therebetween and to project the head coacting edge of the inner rim above that of the outer rim so that the head is drawn taut over and in engagement with the inner rim. In order that the strings may have sufficient clearance over the raised edges of the head the finger board and tail piece are raised sufficiently for such purpose. This raising of the points of attachment of the strings with respect to the head reduces the pressure of the bridge on the head and is therefore detrimental to the volume and quality of tone produced by a playing of the instrument.

The object of the invention is the provision of means in connection with a banjo of this character whereby raising of the head by the inner rim does not change the normal positions of fastening of the strings to the neck and tail piece and causes the bridge to exert a greater tension or pressure on the head than is ordinarily the case, thereby resulting in more perfect tones, as the tone is largely dependent on the tenseness of the strings and pressure of the bridge on the head.

45 The invention is fully described in the following specification, and while, in its broader aspect, it is capable of embodiment in numerous forms, a preferred embodiment thereof is illustrated in the accompanying drawings, in which,—

Figure 1 is a face view of a banjo embodying the invention, with parts broken away. Fig. 2 is an enlarged section on the line 2—2 in Fig. 1, with a part broken away,

and Fig. 3 is an enlarged section on the line 55 3—3 in Fig. 1.

Referring to the drawings, 1 and 2 designate the outer and inner rims, respectively, of the banjo body, which rims are rigidly secured together in spaced relation with the inner rim projecting at its upper edge above the upper edge of the outer rim. The rims or banjo body have the customary neck 3 projecting therefrom. The customary head 4 is stretched across the top edges of the body rims 1 and 2 and held taut by a tension ring 5 secured around the upper edge portion of the outer rim 1 by tension bolts or clamps 6 in the usual or any suitable manner. 7 designates the strings of the banjo which are connected at one end to a tail piece 8 and at their other end to keys at the outer end portion of the neck 3. The strings are held supported above the head 4 by the customary bridge 9. 75

In carrying out my invention the upper edge of the inner rim 2 of the body is cut down or recessed at opposite sides of its axis at points below the strings 7, as shown at 10, to permit the head 4, when drawn taut 80 across the rim, to extend down into such recesses substantially to a depth on a level with the upper edge of the outer rim 1, as illustrated in Fig. 2. This causes an outward bellying of the head with the bow or arc thereof lengthwise of the strings, and enables the customary low points of attachment of the strings to the tail piece and neck relative to the outer rim 1 to be maintained and at the same time provides sufficient clearance between the head and the strings at the points of crossing of the head. 85

The bridge 9 bears downward on the head bow and exerts a considerable straightening 95 out downward pressure on the head when the strings are tightened, thereby tending to straighten out the head bow. The pressure which is thus exerted by the strings on the head in combination with the double 100 rim feature tends to produce full, rich tones of better quality and volume than is otherwise possible, and from a commercial standpoint is found to be of material value.

I wish it understood that my invention 105 is not limited to any specific construction, arrangement or form of the parts, as it is capable of embodiment in numerous forms

without departing from the spirit of the claims.

Having thus described my invention, what I claim as new and desire to secure by Letters Patent, is,—

1. A banjo having its body provided with spaced inner and outer rims with the upper edge of the inner rim projecting above the upper edge of the outer rim except at points 10 below the strings where its upper edge is recessed, and a head drawn over the inner and outer body rims and having portions thrown down into the recesses of the inner rim whereby the head is outwardly bellied.
- 15 2. A banjo having inner and outer spaced body rims with the upper edge of the inner rim projecting above that of the outer rim and recessed at diametrically opposite points, a head drawn taut over the upper 20 edges of the rims in contact therewith and having portions drawn into the inner rim depressions, strings extending over the head above the depressed portions thereof, means

for holding the strings taut and a bridge between the strings and head in the diametrical line of the depressions.

3. A banjo having inner and outer body rims spaced apart with the upper edge of the inner rim extending above that of the outer rim and recessed at diametrically opposite points to a depth substantially flush with the upper edge of the outer rim, a neck extending from the side of the body in the diametrical line of the recesses, a tail piece secured to the other side of the body in the 35 diametrical line of the recesses, a head drawn taut over the upper edges of the body rims with portions extending down into the inner rim recesses, strings connecting the neck and tail piece over the head and recesses 40 and a bridge between the strings and head tending by tension of the strings to depress the head between the rim recesses.

In testimony whereof, I have hereunto signed my name to this specification.

EDWARD N. GUCKERT.
